UNITED STATES PATENT OFFICE.

JOHN TRYGGVI BERGMAN, OF WINNIPEG, MANITOBA, CANADA.

SHEAF-LOADER.

1,124,274.

Specification of Letters Patent. Patented Jan. 12, 1915.

Application filed May 9, 1913. Serial No. 766,583.

To all whom it may concern:

Be it known that I, JOHN TRYGGVI BERGMAN, of the city of Winnipeg, in the Province of Manitoba, Canada, have invented 5 certain new and useful Improvements in Sheaf-Loaders, of which the following is the specification.

The invention relates to a hay and sheaf loader and the object of the invention is to 10 provide an inexpensive, easily operated and efficient machine which will gather up sheaves from the ground and elevate them to a position where they can be readily dumped into a wagon, the machine being readily controlled by a single operator.

It consist essentially in a portable frame mounted on a pair of carriage wheels and a drive wheel, a pick up conveyer at the forward side of the machine, a cross conveyer 20 adjoining the rear end of the pick up conveyer and having a portion thereof horizontally disposed and a portion thereof inclined, a rotatable sweep or spiked wheel adjoining the forward end of the pick up conveyer, an adjustable pan or gatherer pivotally secured to the forward end of the pick up conveyer, controllable means for operating the conveyer and the sweep and means for adjusting the pan, the parts being arranged and constructed as hereinafter more particularly described.

Figure 1 is a front view of the complete machine. Fig. 2 is a plan view of the same. Fig. 3 is a plan view of the frame and the 35 various shafts carried thereby the conveyer being removed. Fig. 4 is an enlarged detailed side view of the drive wheel and adjoining parts. Fig. 5 is a vertical sectional view through the drive wheel. Fig. 6 is a 40 vertical sectional view through the machine, the section being taken in the plane denoted by the line Y—Y' Fig. 2.

In the drawings like characters of reference indicate corresponding parts in each 45 figure.

1 represents a substantially rectangular main frame comprising front and rear beams 2 and 3 and side beams 4 and 5, the side beams extending beyond the front beam 2. 50 6 and 7 represent suitable carriage wheels rotatably mounted on stub axles 8 extending from the beams 4 and 5.

9 represents the main shaft of the machine which is rotatably mounted in the extending 55 ends of the beams 4 and 5.

10 is a ground or drive wheel having the

hub thereof fixed on the shaft at a point adjoining the tongue 11 which is secured permanently to the frame and extends forwardly therefrom.

60

12 and 13 are similar opposing downwardly inclined side pieces permanently carried by the frame and forming supports or bearings for the ends of the pick up conveyer shafts 14 and 15.

65

The shafts carry pairs of chain wheels 16 and 17 connected by chains 18. The chains are connected with cross bars 19 fitted with extending spikes 20.

65

The pick up conveyer is adapted to gather 70 the sheaves from the ground and deposit them on an endless cross conveyer 21 comprising an endless belt 22 fitted with suitably spaced cross slats 23 and carried by endless chains 24 and 25 the chains being 75 mounted on pairs of chain wheels 26 and 27 carried by end shafts 28 and 29 and an intermediate shaft 30. The shafts 28 and 30 are rotatably mounted in suitable bearings carried by the beams 2 and 3 while the shaft 80 29 has the ends thereof mounted in the upper ends of angularly disposed side shields 31 and 32 which extend from the frame and above the wheel 6. The brace bars 33 support the overhanging ends of the shields 85 from the frame.

34 is a back wall or guard plate carried by the frame and continuous with the inner end of the shield 31.

35 is a side wall or guard plate mounted 90 on the beam 5 and continuous with the side piece 13 and having the rear end thereof butted up against the back guard plate.

The rear end of the side piece 12 abuts up against the inner end of the shield 32 to 95 which it is also secured.

36 is a deflecting plate permanently secured to the side pieces 12 and 13 and overhanging the horizontally disposed portion "a" of the said conveyer.

100

The shaft 9 is fitted with a loose sleeve 38 carrying at the opposite ends a beveled pinion 39 and a wheel 40, said wheel 40 having the teeth 41 thereof meshing with the toothed wheel 42 mounted on a stub shaft 105 42' carried by the side piece 12. The chain wheel 42' is coupled to the toothed wheel 42 and operates also on the stub shaft. This chain wheel is connected by a chain 42' with a chain wheel 15' located on the end of 110 the shaft 15. The bevel wheel 39 meshes with the bevel pinion 43 permanently lo-

cated on the extending end of the shaft 30. The sleeve is prevented from end play by a collar 38.

44 and 45 are further chain wheels on the shafts 30 and 28 and 46 is a chain connecting them.

47 is a gathering pan pivotally secured to the forward ends of the side pieces 12 and 13 and having the ends thereof turned upwardly at 48 to prevent material from escaping over the ends of the pan. One of the flanges or upturned ends of the pan is cut away to admit a more or less upright shaft 49 rotatably mounted in the end of the pan and provided at the upper end with a pulley 50 which is connected by a rope, cable or other such drive with a pulley 51 located on the end of the shaft 14 which, it will be noticed, extends beyond the side piece 13.

52 is a spiked sweep or gathering wheel fixed on the lower end of the shaft 49 adjoining the upper face of the pan. The pan is supported adjustably by a lever 53 pivotally secured at 54 to the tongue and having the forward end thereof pivotally connected to a supporting bar 55 permanently secured to the pan. The lever is located within convenient range of the operator's seat 56 mounted on the tongue.

30 The chain wheel 40 is supplied with a number of concentrically arranged openings 40' designed to receive the extending end of a dog 57 pivotally secured at 58 to lugs 59 extending from the hub of the wheel 10.

35 The opposite end of the dog is forked at 60 and spans the shaft 9 clear of the hub of the wheel. A lever 61 is pivotally secured at 62 to the side of the tongue and has the lower end thereof forked at 63 to span the

40 shaft 9 at a point adjoining the forked end of the dog. A spiral spring 64 is connected to the dog and the hub and tends to hold the dog normally against the face of the wheel 40 or in one or other of the openings

45 40'. The upper end of the lever 61 is located within convenient range of the driver's seat.

When the machine is in use it is drawn over the ground by draft animals attached to the tongue 11, the ground wheel 10 rotating as the machine advances. If the driver desires to pick up sheaves on the ground he adjusts the pan by means of the lever 53 and directs the animals so that the 55 sheaves will be picked up by the pan. The sheaves are passed over the pan onto the pick up elevator which passes them to the cross elevator where they are elevated so that they can be dumped onto a wagon 60 which accompanies the machine the wagon being driven so that it will have a position directly beneath the upper end of the cross conveyer.

It is here to be noticed that as shown in 65 the drawings the dog will be held by the

spring in one or other of the openings 40' until displaced by the lever 61. Accordingly the pick up conveyer will be rotated by the wheel 40, the cross conveyer will be operated by the bevel pinion 43 and the 70 sweep will be actuated by the connection 50. If the operator desires to stop the conveyers and sweep he has simply to draw the lever 61 toward him which motion causes the lower end of the dog to be depressed and the upper end to be withdrawn from the opening 40'. A quadrant could be supplied with this lever so that it could be set in two positions, the one position in which the dog is engaged and the other the position in 75 which the dog is disengaged with the wheel. I have not considered it necessary to show or detail this in the drawings as the construction is well known and its application would not amount to invention. It is re- 80 marked however that if a quadrant is supplied the horizontal position of the dog is reversed, that is to say the dog is held normally out of engagement with the wheel 40 so that as the machine was passing over the 85 ground and not picking up sheaves the draft animals would not have the additional weight of the drive. The operator could throw in the dog when he was about to approach the sheaf or sheaves. The sweep is provided to gather in sheaves slightly to the side of the pan as will be readily understood.

What I claim as my invention is:

1. The combination comprising a suitable 100 frame carried rearwardly on carriage wheels and forwardly on a drive wheel, a cross conveyer mounted on the frame and having one end thereof elevated, an inclined pick-up conveyer designed to elevate and deposit 105 material on the endless conveyer, an adjustable pan located in advance of the pick up conveyer, a spiked sweep located at one end of the pan and means actuated by the ground wheel for simultaneously operating all of 110 said conveyers and the sweep, as and for the purpose specified.

2. The combination comprising a substantially rectangular frame, carriage wheels supporting the frame rearwardly, a rotatably mounted drive shaft suitably supported in advance of the frame, a drive wheel fixed on the drive shaft, an endless cross conveyer mounted on the frame and having one end thereof elevated, an inclined pick up 115 conveyer in advance of the cross conveyer and designed to deliver material onto the same, an adjustable pan in advance of the pick-up conveyer, a sleeve mounted on the drive shaft having one end thereof adjoining the drive wheel and fitted with a toothed disk having a number of concentrically arranged openings therein, a spring pressed dog carried by the ground wheel and normally engaged with one or other of the open- 120 125 130

ings, means for releasing the dog from the openings, a bevel pinion fixed on the sleeve, a drive connection between the toothed disk and the pick up conveyer and a drive connection between the bevel pinion and the cross conveyer, as and for the purpose specified.

3. The combination comprising a substantially rectangular frame, carriage wheels supporting the frame rearwardly, a rotatably mounted drive shaft suitably supported in advance of the frame, a drive wheel having the hub thereof fixed to the drive shaft, a sleeve on the shaft of the drive wheel, a toothed disk fixed on the end of the sleeve adjoining the drive wheel, said disk being supplied with a number of concentrically arranged openings, a bevel wheel fixed on the opposite end of the sleeve, a spring pressed dog pivotally mounted on the hub of the drive wheel and having one end thereof normally entering one or other of the openings in said disk and the opposite end thereof forked and spanning the drive shaft, a suitably supported lever engageable with the forked end of the dog and a drive connection between the toothed disk and the inclined conveyer and a drive connection between the bevel wheel and the cross conveyer, as and for the purpose specified.

4. The combination comprising a substantially rectangular frame, a carriage wheel supporting the frame rearwardly, oppositely disposed forwardly directed and downwardly inclined side pieces secured permanently to the front side of the frame, a drive shaft in advance of the frame and having the ends thereof suitably supported from the frame, a drive wheel having the hub thereof permanently secured to the drive shaft, an endless pick-up conveyer located between the side pieces, said conveyer being mounted on suitable top and bottom cross shafts, an endless cross conveyer carried by the frame and designed to receive material deposited from the pick-up conveyer, said cross conveyer having one end elevated and being mounted in the usual way on suitably located cross shafts a sleeve rotatably mounted on the drive shaft and adjoining the drive wheel, a toothed disk fixed on

the end of the sleeve adjoining the drive shaft, said disk being provided with a number of concentrically arranged openings, a bevel wheel on the opposite end of the sleeve, a spring pressed dog pivotally mounted on the hub of the drive wheel having one end thereof normally entering one or other of the openings in the disk and the opposite end thereof forked and spanning the drive shaft, a suitable pivotally mounted lever having the lower end thereof spanning the drive shaft and engaging with the forked end of the dog, a stub shaft secured to one of the side pieces and carrying coupled chain and gear wheels, the gear wheel meshing with the teeth of the disk, a chain wheel located on the lower cross shaft of the pick up conveyer, a chain connecting the latter chain wheels, a bevel pinion located on one of the cross shafts of the cross conveyer and an adjustable pan in advance of the pick-up conveyer, as and for the purpose specified.

5. In a sheaf loader the combination with a suitable wheeled frame, a cross conveyer carried by the frame and having one end thereof elevated and an inclined pick-up conveyer in advance of the cross conveyer, of a pivotally mounted pan located at the forward end of the pick-up conveyer and designed to direct material thereon, means for adjusting the pan and a sweep associated with the pan and located at one end thereof, as and for the purpose specified.

6. In a sheaf loader the combination with a suitable wheeled frame, a cross conveyer carried by the frame and having one end thereof elevated, an inclined pick up conveyer in advance of the cross conveyer and an adjustable pan located in advance of the pick-up conveyer and designed to deposit material thereon, of a spiked rotatably mounted sweep located at one end of the pan and means for operating the sweep, as and for the purpose specified.

Signed at Winnipeg, this 16 day of April, 1912.

JOHN TRYGGVI BERGMAN.
